BOOKLET

John C. Long, Charleston, S. C.

Application December 20, 1950, Serial No. 201,847

3 Claims. (Cl. 282—22)

1

This invention relates to booklets wherein original and carbon copies may be made and to special transfer sheet arrangements and correlated top cover structure in such booklets.

It is a major object of the invention to provide a booklet containing original and duplicate pages in succession and wherein a novel arrangement of carbon sheets is provided so that there is always a bound-in fresh or usable transfer sheet available for insertion between the pages.

A further object of the invention is to provide a novel booklet wherein a plurality of transfer sheets are bound into the booklet above the pages.

A further object of the invention is to provide a novel booklet wherein a plurality of transfer sheets are bound into the booklet above the pages and a special folded top cover contains the transfer sheets not in use while permitting insertion of the lower most sheet between two pages.

Figure 1 is a section through a partially open booklet according to a preferred embodiment of the invention;

Figure 2 is a front elevation looking into the open end of the partially open booklet;

Figure 3 is a section on line 3—3 of Figure 2 illustrating the bound edge enlarged;

Figure 4 is a section like Figure 3 but with the lower carbon sheet slipped between the pages of the top folded paper slip; and

Figure 5 is a top plan view of a closed booklet with the cover partly cut away.

The booklet comprises a relatively stiff rectangular sheet of cardboard or the like 11 beneath which lies a thinner coextensive sheet of cardboard or the like 12. Sheet 11 is sufficiently stiff to serve as a rigid backing for the booklet during writing, and may be of low grade unfinished cardboard. Sheet 12 is essentially a bottom cover of finer surface which adds to the stiffness, but is intended chiefly to improve the appearance. If desired sheets 11 and 12 may be replaced by a single adequately stiff and finished sheet of cardboard or the like.

Superposed above base 11 is a stack of identical folded paper slips 13 each comprising a top original page 14 and a bottom duplicate page 15 of the same size connected at their outer ends by a serrated hinge portion 16. The inner ends of lower pages 15 extend beyond the inner ends of pages 14 into a binding area 17 where they are tightly secured together as by staples 18 which also pass through base 11 and bottom cover 12. Outwardly of staples 18 and underlying the inner

2

edge of page 14 each page 15 is formed with a perforated score line 19 so that it can be torn out of the booklet evenly with page 14.

Above the uppermost slip 13 a plurality of identical carbon transfer sheets 20 are bound into the stack by staples 18. These carbon sheets which may have lines across their inner ends near the binding 17 have their transfer surfaces on the bottom. Above the top carbon sheet 20 is a top cover assembly comprising cover sheet 21 which is thicker than pages 14 or 15 and preferably of about the thickness and finish of sheet 12 is bound into the assembly by staples 18. The entire assembly is rectangular with all sheets and pages being of the same dimensions in plan, except for top cover 21 which at its outer end is folded at 22 to provide an undercover 23 that extends back under the carbon sheet section and terminates at about the level of score lines 19.

When the book is first purchased, all of the carbon sheets 20 are contained by the top cover 21 and undercover 23 as illustrated in Figure 1. In starting use of the booklet, see Figure 5, the lowermost carbon sheet 20 is slipped out from undercover 23 and inserted between pages 14 and 15. The other carbon sheets 20 remain enclosed within the folded top cover assembly, and the user may write upon the top surface of original page 14 while producing a carbon duplicate on page 15.

After the top slip 13 is completed, it is removed from the booklet by stripping of page 15 at score line 19, and then the same lowermost carbon sheet is available to be slipped into the next top slip 13. This is continued until the lowermost carbon sheet 20 is used up or exhausted, at which time it can be torn out at binding 17, and the next lowermost carbon sheet is now available to be slipped out of the cover and used in the above fashion.

In this manner I always have a fresh or usable sheet of carbon available for each top slip 13. This is a great improvement over prior booklets of this type wherein only a single carbon sheet was bound in above the top slip with a few other carbon slips bound in at intervals between predetermined numbers of slips on the theory that each carbon slip would remain usable until the next bound-in carbon slip was reached. If the top carbon sheet in such prior booklets became damaged or useless, there was no bound-in carbon sheet available for the top series of folded slips and the messy slow operation of improvis-

ing and inserting a loose carbon sheet was necessary.

During the entire life of the booklet, the unused reservoir of fresh carbon sheets is held within the top cover assembly and only the carbon sheet being used is free. The undercover 23 not only enfolds the carbon sheets not in use but it protects the user's hands from smearing on the undersurface of the lower carbon sheets in the reservoir.

The invention may be embodied in other specific forms with departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a booklet, a stack of paper slips comprising a bottom leaf having its inner end held in a binding and its outer end connected along a fold line to the outer end of an upper leaf that has a free inner end terminating adjacent said binding, a plurality of superposed transfer sheets held at their inner ends in said binding above said stack of slips and having individually free outer ends, and a top cover assembly having an

undercover portion folded inwardly between said carbon sheets and said slips.

2. In a booklet, a plurality of superposed slips each comprising a bottom leaf bound into the booklet and a top leaf folded back over the bottom leaf to terminate short of the binding, a plurality of transfer sheets bound into said booklet above said slips, and a top cover bound into the booklet having an extension flap having a free end folded to extend between said transfer sheets and said slips, said flap permitting the lowermost bound transfer sheet to be inserted between said leaves while the flap underlies the transfer sheet immediately thereabove.
3. In the booklet defined above in claim 2, said top and bottom leaves comprising original and duplicate leaves with the latter having a perforated tear portion adjacent the binding.
